INVENTOR

JOSEPH ROSNER

BY Joseph Rosner

ATTORNEY

UNITED STATES PATENT OFFICE

155,734

DESIGN FOR A LAMP BASE

Joseph Rosner, Kirkwood, Mo., assignor to Pidgeon Vitrified China Company, Barnhart,
Mo., a corporation of Missouri

Application August 6, 1948, Serial No. 147,977

Term of patent 3½ years

(Cl. D48—20)

To all whom it may concern:

Be it known that I, Joseph Rosner, a citizen of the United States residing at Kirkwood, county of St. Louis, State of Missouri, have invented a new, original, and ornamental Design for a Lamp Base, of which the following is a specification, reference being made to the accompanying drawing forming a part thereof, in which Figure 1 is a front elevational view of a lamp base embodying my new design; Figure 2 is a side elevational view thereof; and Figure 3 is a rear elevational view thereof.

I claim—

The ornamental design for a lamp base, substantially as shown.
